STITCH REMOVING AND CUTTING TOOL

John B. Miller, Gainesville, Ga.

Application November 18, 1952, Serial No. 321,174

1 Claim. (Cl. 7—14.1)

This invention relates to bag openers, and more particularly, has reference to a bag opener of the type adapted to open a bag or similar container the mouth of which has been stitched closed.

I am aware of other bag openers which have been devised, which are adapted for cutting stitches, but to my knowledge, these have not been particularly designed in a manner that will cause said stitches to be effectively tensioned by the opening device when said device is shifted in one direction transversely of the line of stitching, with one of a pair of adjacent, tensioned stitches being cut simultaneously with the lifting of the adjacent stitch in a manner that will free the stitching threads for easy and speedy withdrawal from the bag.

The present invention is particularly designed to accomplish the opening of a bag in the manner referred to above, the device having the functional characteristic of cutting one tensioned stitch simultaneously with the lifting of the stitch next adjacent thereto, in a manner that will facilitate to a marked degree the removal of the entire line of stitching from its bag-closing position.

Another object of importance is to provide a bag opener of the character described which can be manufactured at low cost, in quantity.

Another object is to provide a bag opener as stated which will be so designed as to prevent the cutting edge of the opener from engaging in the fabric of the bag during the opening operation.

Still another object is to provide a bag opener as described which will be particularly designed to permit a removable blade to be incorporated therein.

Still another object of the invention is to provide a bag opening tool of the type referred to that will be rugged, trouble free in operation, and formed without moving parts.

Other objects will appear from the following description, the claims appended thereto, and from the annexed drawing, in which like reference characters designate like parts throughout the several views, and wherein:

Figure 1 is an elevational view of a bag opening tool formed in accordance with the present invention, as it appears when in use, a bag being shown fragmentarily;

Figure 2 is an enlarged elevational view of the tool per se, a portion of the handle being broken away;

Figure 3 is an edge elevational view in which a portion has been broken away;

Figure 4 is a view similar to Figure 2, showing the opposite side of the tool;

Figure 5 is an enlarged transverse sectional view taken substantially on line 5—5 of Figure 3;

Figure 6 is an exploded perspective view, portions being broken away, of a modified form;

Figure 7 is a perspective view of a second modified form; and

Figure 8 is a transverse sectional view, on an enlarged scale, taken substantially on line 8—8 of Figure 7.

Referring to the drawings in detail, the reference numeral 10 indicates a molded, plastic handle capable of being produced in quantity, at low cost, said handle being relatively elongated and flattened, as best shown in Figure 3. The handle 10, for substantially its entire length, can be formed, on opposite faces thereof, with shallow longitudinal depressions 12, to facilitate gripping of the handle while at the same time permitting the handle to be manufactured from a minimum of material.

At its inner end, the handle 10 is integrally formed

2

with a bead 14, said bead 14 serving as a dividing means that separates the handle from a flat shank 16. The shank 16 is integral with the handle 10, being also formed from molded plastic material.

5 The shank 16, when viewed in cross section, may be given the shape of a flattened ellipse (see Figure 5), so that said shank can be considered as having a relatively thick portion extending longitudinally and centrally thereof, said relatively thick portion tapering progressively toward the opposite side edges of the shank.

10 At its outer or free end, the shank 16 is formed with a relatively elongated, V-shaped notch 18, said notch defining, at opposite sides thereof, fork arms 20, 22 integral with the shank.

15 The fork arms 20, 22 are each of pointed formation, and thus, said fork arms are respectively provided with outer side edges 24, 26 that converge in the direction of the outer end of the shank 16. The outer side edges of the fork arms meet the outer ends of inner side edges 28, 30 of said fork arms at the outer end of the shank 16. The inner side edges 28, 30 of the fork arms are also the respective side edges of the notch 18, and as will be noted from Figures 2 or 4, the side edges 28, 30 extend in diverging relation toward the outer end of the shank 16. The inner side edges 28, 30 of the fork arms are disposed at acute angles to one another, the angular relation of said inner side edges being such as to define an acute angle of substantially fewer degrees than the acute angle defined by the outer side edges 24, 26.

20 Referring now to Figure 4, I prefer that the fork arm 20 be tapered not only as to the width thereof, but also as to the thickness thereof, said fork arm 20 being progressively decreased in thickness toward the pointed or outer end thereof, as shown at 32. Thus, the fork arm 20 when inserted in a stitch 33 (see Figure 1) and shifted transversely of said stitch, will tension said stitch not only by reason of the progressively increased width of the fork arm, but also by reason of the progressively increasing thickness of said fork arm.

25 Formed in the inner edge of the fork arm 22 is an elongated longitudinal recess 34, said recess extending from the inner end of notch 18 to a location spaced a short distance away from the outer end of the fork arm 22. The recess 34 is adapted to expose, along the inner edge 30 of fork arm 22, the cutting edge of a blade 36. The blade 36 has a substantially rectangular body tapered to a point, the pointed end of the blade corresponding substantially to the pointed formation of the fork arm 22, as shown in Figure 2.

30 A modified form of blade is shown in Figure 6, and has been designated by the reference numeral 37. This form of blade is exactly like the blade 36, except that the blade 37 has, at its inner end, an arcuate notch 38 interengageable with a node 40 formed on the shank 16. The purpose of this arrangement is to insure the fixed positioning of the blade 37, when said blade is attached to the shank 16.

35 Formed in the blade 36, intermediate the opposite ends of said blade, is an opening 42 adapted to receive a rivet 44 or equivalent fastening element. In this connection, the blade 36 is seated in a complementarily formed, shallow recess 46 formed in the top face of the shank 16, and extending over substantially the full area of the fork arm 22. When the blade 36 is seated in the recess 46, and the rivet 42 is applied to hold the blade in position, said blade will be held against movement relative to its associated fork arm 22. In this connection, it will be observed that the blade 36 is so disposed upon the fork arm 22 as to cause the cutting edge of the blade to be disposed angularly to the outer side edge 26 of the fork arm 22. Thus, the cutting edge of the blade 36 and the outer side edge 26 of the fork arm converge in the direction of the outer end of said fork arm. Therefore, when the tool is inserted in a stitch 47 (see Figure 1) adjacent the stitch 33, and is shifted transversely of the stitch, the stitch 47 will be tensioned by the fork arm 22, by reason of the progressively increasing width of said fork arm 22. As the stitch 47 is tensioned, the cutting edge of the blade 36

will be forced with increasing pressure against the thread, until the stitch is suddenly cut.

It will be readily apparent that the tool, when used in the manner described above, will cause the adjacent stitches 33, 47 to be simultaneously tensioned. After the stitches have been tensioned to a predetermined extent, the stitch 47 will be cut, and the fork arm 20 will, simultaneously with the cutting of the thread, lift the stitch 33. As a result, at opposite sides of a bag B there will be provided loose threads, which, when pulled, will remove the entire line of stitching.

Referring to Figure 6, I have here shown a construction wherein the blade is removable, rather than permanently attached to the shank in the manner shown in Figures 1-5. In Figure 6 there is illustrated a screw 48, extendable through an opening 50 formed in the blade 37, said screw being threadable into a complementarily threaded recess 52 formed in the fork arm 22, and communicating with the shallow recess 46 of said fork arm.

As a result, when the blade 37 becomes dull, it can be removed and a new blade substituted in a minimum amount of time.

Of course, the screw 48 could be utilized in the form of the invention shown in Figures 1-4, with or without the interengaging lock means defined by the notch 38 and node 40. Conversely, the riveted connection could be employed with the interengaging notch 38 and node 40.

In the form of the invention shown in Figures 7 and 8, there is a handle designated generally by the reference numeral 54 having a longitudinal, blade-receiving recess 56 extending along one side thereof. The handle 54 is not unlike a common jack-knife handle, and carries a blade 58 pivotally connected to one end of the handle by a pin 60. The blade 58, when not in use, can be swung into the recess 56.

The blade 58 is formed from an elongated length of flat metal material, and has a back edge 62 extending in slight angular relation to a cutting edge 64. The edges 62, 64 diverge in the direction of the outer or free end of the blade 58, thus to progressively widen the blade in the direction of said free end thereof.

Short of the free end of the blade, the back edge 62 merges into a curved outer edge portion 66, while the cutting edge 64, close to the outer end of the blade 58, merges into a curved outer edge portion 68, the edge portions 66, 68 converging in the direction of the outer end of the blade.

An elongated longitudinal notch 69 opens inwardly from the outer end of the blade 58, and is disposed obliquely to the longitudinal center line of the blade, said notch defining fork arms 70, 72. The fork arm 70 is somewhat wider than the fork arm 72, as shown in Figure 7.

The construction illustrated in Figures 7 and 8 has operating characteristics similar to those obtained when the forms shown in Figures 1-6 are used. In other words, the fork arm 72 constitutes a lifting arm analogous to the fork arm 20, the fork arm 70 constituting a cutting arm analogous to the fork arm 22. When the blade 58 is shifted transversely of a line of stitching,

the fork arm 72 will engage under the stitch 33, while the fork arm 70 will engage under the stitch 47. Continued movement of the device transversely of said line of stitching will be effective to tension both of said stitches, and the stitch 47 will suddenly be cut, simultaneously with the lifting of the stitch 33.

It should be noted that in the form of the invention shown in Figure 7, it is not essential that the cutting edge of the fork arm 70 be the outer side edge of said fork arm. The cutting edge could, instead, be the inner side edge of the fork arm 70, or, if desired, both the inner and outer side edges of the fork arm 70 could be sharpened.

In all the forms of the invention it is desirable, however, that the tips of the fork arms be rounded off or dulled, so as to prevent said tips engaging the fabric of the bag B when the tool is in use. Further, rounding off or dulling of the tips of the fork arms permits the tool to be inserted in one's pocket without danger of injury to the person or his garments.

With further reference to the form of the invention shown in Figure 7, it might be desirable that the blade 58, which is analogous to the shank 16, be formed of a relatively inexpensive, unsharpened metal material. Then, the fork arm 70 could be constituted as a removable blade, capable of being screwed to or otherwise fixedly attached to the blade or shank 58.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

A bag opening tool comprising a handle; a shank extending therefrom having an outer end formed with a V-shaped notch opening inwardly from said outer end and extending longitudinally of the shank, said notch defining at opposite sides thereof a pair of fork arms on the shank widened progressively in a direction toward the handle, one of said fork arms constituting a stitch-lifting arm and being extendable under a stitch to tension and lift the same when the shank is shifted transversely of the stitch, the other fork arm having a cutting edge recessed into the inner side of said fork arm to tension and cut a stitch immediately adjacent to the first stitch, said cutting edge being part of a blade removably secured in a matching slot on said other fork arm.
